UNITED STATES PATENT OFFICE.

HENRY K. SANDELL, OF CHICAGO, ILLINOIS, ASSIGNOR TO HERBERT S. MILLS, OF CHICAGO, ILLINOIS.

SHEET-PERFORATING MACHINE.

1,423,738.

Specification of Letters Patent. Patented July 25, 1922.

Application filed December 6, 1920. Serial No. 428,539.

To all whom it may concern:

Be it known that I, HENRY K. SANDELL, a citizen of the United States, residing at 221 South Green Street, Chicago, in the county of Cook and State of Illinois, have invented a new and useful Improvement in Sheet-Perforating Machines, of which the following is a specification.

My invention relates to an improvement 10 in the class of perforating machines, such as are used for producing the music-sheets employed in self-playing instruments, in which the perforations are made by reciprocating punches rapidly actuated to cut those of the 15 perforations which are elongated by so feeding the sheet being acted upon as to produce the perforations by successively overlapping punch-cuts.

A machine in the class referred to is the 20 subject of United States Patent No. 907,530, dated December 22, 1908, in which the punches are electrically operated, as they preferably are in the present machine.

A primary object of my present invention 25 is to cause the punches to operate with comparatively great rapidity—in fact, those in the machine hereinafter shown and described, and which has long been in practical use, are reciprocable 3500 times per minute; 30 and to accomplish that purpose and avoid vibrations of the machine in operation so severe as to be detrimental to its mechanism, the machine is of relatively simple and light construction, involving comparatively few 35 parts.

I have more especially designed my improved machine for producing master-rolls from which to duplicate sheets for music-rolls in another machine, such as that of the 40 said patent, though it may be used like the latter. I have thus far used it for the master-roll producing purpose by operating it electrically from a key-board like that of a piano or organ, by causing playing of the 45 keys to control electric circuits containing electromagnets for operating the armatures of the latter to effect operation of the punches, and for that purpose electrically connected with those circuits, at the electrical contacts controlled by the keys, the 50 circuits of the electric self playing violin of United States Patent No. 855,021, dated May 28, 1907, to cause the perforating machine to

translate the violin-playing to the sheet undergoing perforation. 55

In the accompanying drawings, Figure 1 is a broken view in front elevation of my improved perforating machine; Figure 2 is a section on line 2—2, Fig. 1; Figure 3 is a broken sectional view showing one of two 60 similar centrally fulcrumed levers and a guided block reciprocated by it; Figure 4 is a diagrammatic, partly sectional representation of the punch-mechanism, showing the means, duplicated for each of the many 65 punches, for co-operating with a punch-driving and retracting device, said means comprising a lever-operated spring retracted abutment-rod for engaging at its upper end the rear end of a punch, and electromagnets 70 with the armatures of which the levers are connected for operating them by wires; Figure 5 is an enlarged broken perspective view of one of the plurality of similar punches; Figure 6 is an enlarged broken sectional 75 view, the section being taken on line 6, Fig. 2, and Figure 7 is an enlarged broken perspective view of a comb-like slotted guide-block in which the aforesaid abutment-bars and levers work. 80

The frame of the machine comprises two cheeks, 8 and 9, connected by a back-plate 10 containing a horizontal opening 11. To the face of this back-plate is bolted a head 12 containing a horizontal forwardly flaring 85 discharge-opening 11^a for the cuttings, registering with the opening 11. A female-die plate 13 is let into the head 12 to register its die-openings 13^a with the slot 11^a; and a rearward extension 12^a of this head has 90 formed in it a passage 12^b for the sheet to be perforated and contains a horizontal series of punch-guiding openings 12^c registering with the die-openings 13^a. To the face of the head-extension 12^a two similar 95 angle-bars 14, 14 are bolted through their vertical webs to project the horizontal webs at opposite sides of the horizontal center of the head-extension in parallel relation to each other and form a passage-way 14^a, 100 across which the punches are reciprocated as hereinafter explained.

The preferred form of punch used is that most clearly illustrated at 15 in Fig. 5, showing it to be of cylindrical shape with 105 a bifurcated forward cutting point and a

finger 15^a extending at a right-angle from it at a suitable point between its ends. The punches work at their cutting ends through the guide-openings 12^c and the space 14^a 5 between the angle-bars, in the rear edges of which slots 14^b are provided, in staggered relation from one angle-bar to the other, (see Fig. 6) to receive and reciprocatingly confine the punch-fingers 15^a, these slots being closed at their outer ends by a bar 16 10 covering them and for that purpose connecting the angle-bars at the edges of their horizontal webs. The punches also work through the bar 16 which supports their rear 15 ends. Edge protrusions are shown to be provided at 89 on the frame-cheeks 8 and 9. Between these protrusions extends a slotted guide-bar 17 having offset end-legs 17^a rigidly fastened to the inner faces of 20 the cheeks, between which and the ends of this bar are formed spaces for reciprocably confining therein blocks 18 having shoulders 18^a and tongues 18^b on their rear ends to pass through openings 19^a in bearings 19 25 extending inwardly from the cheek-protrusions 89. Secured at its ends to and connecting the blocks 18 at parts thereof behind their shoulders, is a push-bar 20 extending lengthwise over the guide-bar 17. 30 A thin-metal plate 21, of angular cross-section, covers and is secured to the push-bar 20 and extends thence against the block-shoulders 18^a and over the blocks, to which it is secured, and the forward edge of the 35 plate is bent downwardly to form a catch 21^a to engage punch-fingers 15^a projecting into its path for retracting the punches as hereinafter described; and another sheet-metal plate 22 connects the higher sections 40 of the blocks 18 at their lower sides and is bent upwardly at its forward edge to form a catch 22^a for engaging depending punch-fingers 15^a for the punch-retracting purpose. The fingers 15^a on alternate punches 15 project upwardly through the slots 14^b in the 45 horizontal web of the upper angle-bar, and the fingers on intermediate punches project downwardly through the slots 14^b in the corresponding web of the lower angle-bar, 50 these slots being sufficiently elongated to permit guided reciprocation in them of the punch-fingers.

The bar 17, hereinbefore referred to as being slotted, is provided in its forward edge with a series of rectangular slots 17^b, each directly below the rear part of a punch. On the face of a backing plate 23^a on a bar 23 connecting the frame-cheeks toward their lower ends near their edges, is secured to 55 60 65 70 75 80 85 90 95 100 105 110 115 120 125 130

the keys on the aforesaid key-board. In each slot 24^a is loosely confined at its lower-end portion, to be vertically reciprocable, a flat rod 25. These rods extend upwardly through the slots 17^b in the bar 17 and each 70 normally registers at its upper end with the rear end of a punch, being resiliently held in that position by a spring 25^a connecting it, as clearly shown in Fig. 2, with a stationary ledge-bar 25^b secured on the bar 23. 75 A fulcruming bar 26 is fastened at its ends to the face of the bar 23 and has levers 27 fulcrumed between their ends in slots in its upper edge, the shorter lever-arms extending into the slots 24^a in the plate 24 80 underneath the guidingly confined rods 25. Each lever is connected by a thin wire 28 with the pivotal armature 29^a of an electromagnet 29. To save space, the electromagnets are supported at the base of the 85 mechanism illustrated in Figs. 1 and 2, in pairs, as shown in Fig. 4, and I habitually support them for the same purpose in staggered relation in banks (not shown), each comprising a series of such pairs. 90

A sheet 30 to be perforated is provided in a roll on a spool 31. The spool is shown in Fig. 1 to be journaled in the upper end of the frame on a divided shaft, one section of which is shown at 32 to be spring-pressed 95 and the opposite section carrying on its outer end a wheel 33 having its periphery engaged by a spring-pressed brake 34 to maintain the sheet taut in paying out from the spool. The sheet passes from the spool through 100 the passage 12^b across the line of punches and thence between feed-rolls 34 and 35. The roll 35 is shown in Fig. 1 to have a worm-gear drive connection with the shaft of a suitably supported electric motor 36, 105 and the shafts of the two rolls are shown at 37 to be geared together to revolve for the sheet-feeding purpose.

The punch-driving mechanism remains to be described:

A drive-shaft 38 journaled in end-bearings in the frame-cheeks 8 and 9 carries on one end a pulley 39 having an endless-belt connection 40 with an electric motor (not shown). On each end of the drive-shaft 115 is secured an eccentric 41 having an arm 42, extending from its strap; pivotally connected with one end of a rocking lever 43. The two rocking levers are supported on a shaft 44 passing through them midway between 120 their ends and being journaled at its ends in bearings in the opposite frame cheeks; and each lever 43 is pivotally connected at its opposite end with the outer face of a reciprocating block 18, as represented in Fig. 3. 125

The foregoing description of the mechanism will enable the operation to be readily understood from the following explanation:

The sheet 30 should be fed by the rollers 34 and 35 at the rate of speed at which the 130

automatic translating violin, hereinbefore referred to, is playing, and that speed for the travel of the sheet is preferably about eleven feet per minute.

5 Rotation of the motor-driven shaft 38 causes the eccentrics 41 to rapidly rock the levers 43 and reciprocate the blocks 18. Each closure of a circuit containing an electromagnet 29 energizes it to attract its 10 armature with the effect on the respective wire 28 of turning the lever 27 connected with it in the direction to advance the respective spring-retracted rod 25 and protrude it past the rear end of a punch alining therewith into the path of the push-bar 20 on the reciprocating blocks 18. Each 15 forward stroke of the blocks 18 under the vibrating movements of the levers 43 causes the push-bar to encounter the ends in its path of rods 25 and press them against the punches in their paths to drive the punches and perforate the sheet. In each back-stroke of the blocks 18 and push-bar 20, the catches 21^a and 22^a, by engaging the fingers 25 15^a on the advanced punches, retract the latter. As will be apparent, each initial advance-stroke of any punch produces a more circular hole in the sheet 30; and the duration of the attraction of an armature by its 20 electromagnet determines the length of the resultant perforation. In the steady feeding of the sheet 30, the very rapid reciprocations of a punch under more or less enduring attraction of its controlling armature obviously 25 produces the elongated perforation by successively overlapping cuts, which are so close together as to produce the serrations in its edges in such fine degree as to be scarcely visible to the naked eye, so that 30 those edges are practically smooth.

An important feature of my improved machine is the comparative lightness of the punch-actuating mechanism, whereby it is adapted to be reciprocated against such 45 slight resistance that the latter may be overcome by relatively short leverage; so that the arms of the levers 43 may be of equal length, enabling them to be centrally fulcrumed on the shaft 44, whereby the resistance 50 on their opposite ends is so nearly balanced that the resultant effect in the working of the machine is its operation with vibratory action so light as to avoid detrimental pounding and consequent impairment 55 of the mechanism.

The complicated structure of any perforating machine in the present class has rendered necessary the foregoing rather minutely detailed description of the particular 60 mechanism in which my invention is preferably embodied. I realize, however, that considerable variation is possible in the details of construction thus specifically shown and described, and I do not intend by illustrating a single specific or preferred em-

bodiment of my invention to be limited thereto, my intention being, by the following claims, to claim protection upon all the novelty there may be in my invention as broadly as the state of the art will permit. 70

I claim:

1. In a sheet-perforating machine, the combination with reciprocating punches, of actuating mechanism therefor including reciprocating means engaging the punches to 75 positively advance and retract them, a lever fulcrumed between its ends and operatively connected at one end with said means, and a drive-shaft carrying an eccentric having an arm with which the opposite lever-end 80 is pivotally connected for reciprocating said means.

2. In a sheet-perforating machine, the combination with reciprocating punches, of actuating mechanism therefor including reciprocating means engaging the punches to 85 positively advance and retract them, a centrally-fulcrumed balanced lever operatively connected at one end with said means, and a drive-shaft with which the opposite lever-end 90 has an eccentric connection for reciprocating said means.

3. In a sheet-perforating machine, the combination with reciprocating punches, of actuating mechanism therefor including reciprocably supported blocks carrying means 95 engaging the punches to positively advance and retract them, levers fulcrumed between their ends and connected at one end with said blocks to reciprocate them, and a drive-shaft with which the opposite lever-ends 100 have eccentric connection for reciprocating said blocks.

4. In a sheet-perforating machine, the combination of punch-actuating mechanism 105 including reciprocably supported blocks, a push-bar connecting said blocks and levers fulcrumed between their ends and connected at one end with said blocks to reciprocate them and the push-bar, and eccentric driving means connected with the opposite ends 110 of the levers to oscillate them.

5. In a sheet-perforating machine, the combination with a frame, of a female punch-die and a punch-guide forming with 115 said die a passage for the sheet to be perforated, punches supported to work through said guide and passage into said die and provided with fingers, reciprocably supported blocks, a push-bar connecting said blocks, catches 120 operated by the push-bar to engage the fingers for retracting the punches, levers fulcrumed between their ends and connected at one end with said blocks to reciprocate them and the push-bar, driving means connected with the opposite ends of the levers to oscillate them, spring-retracted rods movable into the path of the push-bar behind the punches, automatically operated mechanism 125 for advancing said rods against their spring- 130

resistance, and means for feeding through said passage a sheet to be perforated.

6. In a sheet-perforating machine, the combination with a frame, of a punch-die in horizontal position in the frame and a punch-guide forming with said die a passage for the sheet to be perforated, punches supported to work through said guide and passage into said die and provided with fingers, blocks supported to reciprocate horizontally at the ends of the punch series and connected by a push-bar, catches operated by the push-bar to engage the fingers for retracting the punches, levers fulcrumed between their ends and connected at their lower ends with said blocks to reciprocate them and the push-bar, driving means connected with the opposite ends of the levers to oscillate them, spring-retracted upright rods raisable into the path of the push-bar behind the punches, automatically operated mechanism for raising said rods against their spring-resistance, and means for feeding through said passage a sheet to be perforated.

7. In a sheet-perforating machine, the combination with the punches and power-operated advancing and retracting mechanism therefor, of spring-retracted rods movable into the path of said mechanism behind the punches, levers extending at one end into engagement with said rods, electromagnets, and light wires immediately connecting the opposite lever-ends with the electromagnet-armatures for turning the levers to advance the rods into said path by energizing the electromagnets.

8. In a sheet-perforating machine, the combination with a frame having supported thereon punches and power-operated advancing and retracting mechanism therefor, of a plate secured on the frame and provided with transverse slots in line with the punches, spring-retracted rods movably confined at one end in said slots to extend at their opposite ends into the path of said

mechanism behind the punches, levers fulcrumed between their ends adjacent said plate to extend at one end into its slots at an angle to and into engagement with said rods, electromagnets, and light wires each immediately connecting a lever with the armature of a different electromagnet for turning the lever to advance the rod engaged by it into said path by energizing the respective electromagnets.

9. A sheet-perforating machine comprising a frame having journaled therein a shaft for a roll of the sheet to be perforated, a female die at the back of the frame and an apertured punch-guide facing said die to form therewith an interposed passage for said sheet, means for feeding the sheet through said passage, slotted angle-bars on said guide, punches reciprocably supported in said guide to work across said passage into the die and having fingers projecting through the angle-bar slots, blocks reciprocably supported at opposite sides of the frame and having a push-bar connection, catches operated by the push-bar to engage the punch-fingers for retracting the punches, a drive-shaft journaled in the frame-sides and carrying eccentrics, levers fulcrumed between their ends and connected at one end with the eccentrics to be oscillated thereby, the opposite ends of the levers being connected with the blocks to reciprocate them, a plate on the frame provided with transverse slots alining with the punches, spring-retracted rods movably confined at one end in said slots to extend at their opposite ends into the path of the push-bar behind the punches, levers fulcrumed between their ends adjacent said plate to extend at one end into its slots at an angle to and into engagement with said rods, and automatically operating mechanism connected with said levers for operating them to advance the rods into said path.

HENRY K. SANDELL.
